UNITED STATES PATENT OFFICE.

HENRY F. NEWBURY, OF NEW YORK, N. Y., ASSIGNOR TO ELEVATOR SUPPLY & REPAIR COMPANY, A CORPORATION OF ILLINOIS.

SIGNAL APPARATUS.

1,132,606.

Specification of Letters Patent.

Patented Mar. 23, 1915.

Application filed November 26, 1904. Serial No. 234,358.

To all whom it may concern:

Be it known that I, HENRY F. NEWBURY, a citizen of the United States, residing in the borough of Brooklyn, city of New York, county of Kings, and State of New York, have invented certain new and useful Improvements in Signal Apparatus, of which the following is a full, clear, and exact description, reference being had to the drawings accompanying and forming a part of the same.

This invention relates generally to signal apparatus in which a person at a given point or station can cause a portion, normally in an inoperable condition, to move or be put into an operable condition and a signal to be given by the movement of a car or similar moving object as it approaches a given point and to restore the parts to their normal condition.

Among the objects of the present invention are the provision of an apparatus or signal system which is simple, practical and efficient as compared with prior devices, and one of the other objects is to improve generally the principles of operation of the system and parts thereof.

The invention consists in the combinations of parts, members or devices herein-after set forth and particularly pointed out in the claims, which form a portion of this specification.

Like letters of reference, wherever they occur, indicate corresponding parts in all of the figures of the drawings.

Figure 1 shows diagrammatically and partly in front elevation one embodiment of the present invention, only a portion of the apparatus for two stations or floors being shown, the same being arranged for signals in a car or similar place and at each of the stations or floors. As shown the upper of the two sets of devices is arranged to give signals, when such portion is in operable condition, as a car or similar object moves upwardly, and the other portion is likewise arranged to give signals as such car or object moves downwardly. Fig. 2 illustrates partly in section and partly in plan that which is shown in Fig. 1 on line 2-2 thereof, with the switch devices in operable condition or positions, but with the switch devices arranged as it is preferred to arrange them in practice, that is, one of them directly in front of the other, so far as the

terminals, retaining devices and moving parts are concerned. Fig. 3 illustrates portions of some and the whole of others of the parts seen in Fig. 2, but with the switch devices in their normal or inoperative condition or positions, that is, where such devices are not operable to close the circuit or circuits by the means provided for that purpose. Fig. 4 illustrates a switch device before any portion of it has been operated to close a circuit through the terminals shown. Fig. 5 shows the same parts, but after the circuit has been closed and the holding means have been operated to hold or retain the circuit closed and the means which coacted with the switch device to close the circuit has moved out of coacting relation therewith. Fig. 6 illustrates two of the switch devices, as seen in Figs. 2 and 3, one of which has been operated to close its circuit or circuits by its coacting means and the other has not been thus operated, the parts being shown when in the positions seen at the lower right hand corner of Fig. 1, but turned so as to show in Fig. 6 the opposite sides of the parts seen in Fig. 1, the corresponding parts being arranged in the preferred way. Fig. 7 illustrates in end view the parts of the switch devices seen in Figs. 2 and 3 as when looking toward the left and nothing is in front of them and when one has been operated as seen in Fig. 6. Figs. 8, 9 and 10 illustrate detached parts seen in preceding figures. Figs 11 and 12 illustrate in front and edge view, respectively, the coacting means for actuating two switch devices when the same are arranged in the preferred manner, instead of diagrammatically, as seen in Fig. 1, where the corresponding parts are shown set back from one another to better illustrate the construction of the parts. Fig. 13 illustrates a modified arrangement of the parts seen in Fig. 2, and where there is a single switch device mounted to move in two directions instead of two as shown in preceding figures and a part, substantially as shown in Fig. 9, is used solely for the purpose of moving the switch device in one direction, that is, from the operable condition or position to the normal or inoperative one, instead of doing this work and in addition closing a circuit or circuits, as in Figs. 1 to 8, inclusive. Fig. 14 illustrates in edge view the actuating means for actuating the switch

device and for moving such device from the operable into the inoperable condition. Fig. 15 illustrates in plan view the parts seen in Fig. 13. Fig. 16 illustrates some of the parts seen in Figs. 13 and 15 when partially operated. Fig. 17 illustrates the same parts when the actuating means moves in the opposite direction to that in which it is assumed to be moving in Fig. 16. Fig. 18 illustrates the parts seen in Figs. 13 and 15 in end view when looking from right to left and the actuating means are omitted. Fig. 19 shows in front elevation, with the controller partly broken away, a modified form 15 of switch devices and means of actuating the same and of moving the switch devices from the operative to inoperative or normal condition. Fig. 20 shows in plan view some of the same parts that are seen in Fig. 20 19. Fig. 21 shows in front elevation some of the parts seen in Fig. 19, but in different positions as when being operated. Fig. 22 shows in front elevation another form of switch device where only one of the terminals is mounted on the controller.

In the construction shown in Figs. 1 to 12 inclusive, two switch devices are employed which are largely duplicates of one another, one of which closes the circuit for a signal 30 device in the car and the other to close the circuit for the signal device at the floor or station, as the car is moving in one direction. These switch devices are shown in Fig. 1 as arranged diagrammatically, that is not directly in front of one another, as they naturally would be arranged in practice. This is done to more clearly indicate the two switch devices and to distinguish one from the other. This necessitates the placing of the 35 actuating means correspondingly one not fully overlapping the other as seen. In Figs. 2 to 12, inclusive, where two switch devices are shown, here one is directly in front of the other, as they would preferably be placed 40 in practice to engage with the movable parts of the switch devices. Also as shown in Fig. 45 1 two pairs or pluralities of these switch devices are mounted on a movable bar or controller, one pair to be actuated by one actuating device, as one car moves in one direction, and the other pair to be actuated by another and separate but similar actuating device, as another car moves in the same direction. As seen in Fig. 1 there are only 50 two of these sliding bars or controllers, one, (the lower one of the two,) for use as the cars move downwardly and the other for use as the same cars move upwardly, and these two controllers are somewhat widely separated from one another. It is designed where 55 several adjacent floors or stations are to be served by the signal apparatus that two of these controllers or bars are to be used for each floor or station served, except the first 60 and last ones where one may be made use of,

if desired. These controllers and switch devices shown in this Fig. 1 are arranged far enough apart to have pairs of these controllers arranged within the space between the two shown. These controllers may be arranged any desired distance apart, but it is preferred that they be arranged in a somewhat narrow or confined space, as for instance, each pair within a space in one direction, say one and one half or two inches for each twelve feet of movement or travel of the elevator car or similar object. Thus, if there is a distance of twelve feet between the floors of a building the controllers may for each floor occupy two inches in the direction that the actuating means travel past the switch devices, or each pair of controllers may occupy that space, or one of one and one half, or two and one half inches space, as the constructor sees fit to construct the apparatus. 70 75 80 85

The actuating means, one for each elevator car or similar object to be served, are preferably connected with the car operating mechanism by suitable speed reducing means of any desired construction in any well known manner, as, for instance, mechanical indicators are many times connected, so as to move a certain distance while the car is moving another certain distance. As the use of these speed reducing devices and the manner of using them are so well known they are not represented in the drawings, it being understood that some form of means be employed connecting with each of the carriages or actuating means C and C' shown in the drawings. The several combinations of members or devices herein set forth necessarily have the same mode of operation whether the carriage or carriages are moved by one kind of means or another, or are moved by the hand of a person, using a rope and pulley, or otherwise. 90 95 100 105

Two cars, A and A', are diagrammatically indicated by inclosed rectangular spaces near the top of Fig. 1, in each of which a signal device, as G, or G', is likewise indicated by a circle. These signal devices are each operable as the car in which it is placed moves in either of two directions, and the construction and arrangement of the parts are such that the device is operated and the signal given as the car approaches the floor or station, whether it is moving in one or the other direction. Carriages C and C', as here shown, are practically duplicates of each other and each is mounted to move independently of the other, there being as many of these carriages as there are elevator cars, or other objects, to be served by any given system or apparatus. As shown, the carriages C and C' are mounted to move relatively to the controllers and switch devices in suitable rollers, as f, f', f'', f''', &c., properly mount- 110 115 120 125 130

ed in the frame F, three pairs of these rollers being seen in connection with each carriage. It is preferred that when rollers are used, as shown, that each carriage shall be 5 within the grasp or control of at least two pairs of such rollers, so that the carriage shall be properly guided and held at all times. As here shown, each switch device, as B, B', B², and B³, consists of a pair of terminals, as b, b', b² and b³, connecting with a circuit, which is closed when the two terminals are in contact, a movable part adapted to bring such terminals into contact, an actuating part adapted to move the 10 movable part in one direction and to engage with actuating means mounted to move past the switch device and means adapted to hold the circuit closed after the terminals are brought into contact by the movement of 15 the actuating means. As thus shown, the actuating parts, as a, a', a², and a³, Fig. 1, are actuated by engaging with portions c, c', c², and c³ of the carriages or actuating means C and C', respectively, and parts, as 20 a⁴, a⁵, a⁶ and a⁷, are actuated by engaging with portions of the carriages or means as c⁴, c⁵, c⁶ and c⁷, respectively. The portions or parts of the carriages or actuating means, c, c', c² and c³, are practically duplicates of 25 one another, and this is also the case with the portions or parts c⁴, c⁵, c⁶ and c⁷, half of each of such portions being for use as the carriages move in one direction and the other half for use as such carriages move in 30 the other direction. As seen in Fig. 1 the actuating and movable parts of the switch devices nearest the controllers are the larger or longer than those which are farther away from the controllers. The actuating parts 35 a, a', a² and a³, when moved in one direction by engaging with actuating means C or C', actuate the movable parts e, e', e² and e³, respectively, and actuating parts a⁴, a⁵, a⁶ and a⁷, likewise actuate movable parts e⁴, e⁵, e⁶ and e⁷, respectively. The movable parts 40 and actuating parts of each pair of switch devices, as B and B', are mounted on a single stud, so as to turn thereon, and each individual switch device is provided with a 45 retaining device to retain or hold the circuit closed, after the actuating and movable parts of that switch have been moved sufficiently for the retaining device shown to engage with the movable part thereof and prevent the spring action of the pair of terminals of that device from moving such movable part. The studs, upon which the movable and actuating parts of each pair of 50 switch devices are mounted are in turn mounted in the controllers, D and D'. The stud d is shown as mounted in the left hand portion of controller D, and it receives the movable and actuating parts of switch devices B and B'; the stud d², mounted in the 55 same controller, receives the movable and

actuating parts of switch devices B⁴ and B⁵; stud d', mounted in the left hand portion of controller D', receives the movable and actuating parts of switch devices B² and B³, and stud d³ mounted in the same controller, 70 receives corresponding parts of switch devices B⁶ and B⁷.

As thus shown in Figs. 1 to 12, inclusive, retaining devices I, I', I², &c., respectively, coact with the movable parts of switch devices B, B', B², &c., respectively, retaining device I' being seen in position, to retain or hold the terminals of switch device B' closed, irrespective of the movements of the controller and actuating part e⁴ of that 75 switch device, until such retaining device has been moved out of retaining position by engaging with a part carried by the carriage or actuating means C mounted to move relatively to such switch and retaining devices. As shown in Fig. 1 switch device B' has been operated and the terminals b' are closed, while switch device B has not been operated, and will not be until the portion c of the carriage or actuating means C 80 has engaged with actuating part a and moved it far enough to bring the terminals of that device into contact. Controllers D and D' are movable in bars Y and Y' suitably mounted on the frame F to receive them, as shown, and permit the controllers to move back and forth therein, so as to render the switch devices operable or inoperable, accordingly as the controller is moved 85 in one direction or the other. These controllers, as shown, are moved in the direction to bring the switch devices into operable condition or position by suitable springs whose tension or stress always or continuously tend to move the controllers in 90 this direction. These controllers are moved against the stress or tension of such springs by the actuating means coacting with the actuating parts attached to the controllers. Controller D is moved in the direction to bring the switch devices mounted thereon into operative condition or position by spring E, and controller D' is similarly moved by spring E'. Controller D is held 95 or maintained in the inoperable condition or position by a projection on armature m of electromagnet M, and controller D' is similarly held by a similar projection on armature m' of magnet M'. These controllers are released from the holding action of 100 these armatures, as m and m' by energizing the electromagnets, as M and M', respectively. 105 The controllers are released from the holding action of these armatures, as m and m' by energizing the electromagnets, as M and M', respectively. 110 The controllers are released from the holding action of these armatures, as m and m' by energizing the electromagnets, as M and M', respectively. 115 The controllers are released from the holding action of these armatures, as m and m' by energizing the electromagnets, as M and M', respectively. 120 The controllers are released from the holding action of these armatures, as m and m' by energizing the electromagnets, as M and M', respectively. 125 The controllers are released from the holding action of these armatures, as m and m' by energizing the electromagnets, as M and M', respectively. 130

seen in Figs. 2 and 3, the same being shown with parts in different positions in the two figures. Another pair of the same is shown in Fig. 6, (with one of the retaining devices 5 partly in section,) turned one half over, so as to bring the devices in front of the controller to which they are attached. The same devices are seen in end view in Fig. 7, as when looking from left to right. The 10 pair thus shown consists of switch devices B⁶ and B⁷, seen in Fig. 1, and the terminals b⁷ of device B⁷ are seen closed, while the terminals b⁶ of device B⁶ are open.

In Fig. 2 switch devices B and B' are seen 15 with the parts in the positions they occupy, when the controller is moved, as shown in Fig. 1, that is, when the switch devices, or portions of them, are in position to be operated and close the circuits connected there- 20 with, or in operable condition. Controller D and these same switch devices are shown in Fig. 3 in the other, or their normal, po- 25 sitions or condition, that is, when the controller has been moved against the stress of spring E by the action of the carriage or ac- 30 tuating means upon the switch devices, and projection m² on armature m of magnet M has engaged with pin or projection g on controller D, so as to maintain or hold the 35 controller against the stress of its spring and keep the switch devices in an inoperable, or their normal condition. When mag- 40 net M is energized armature m is brought into the position seen in Fig. 2 and the stress 45 of spring E moves the controller, and the switch device or devices carried thereby, into the position there seen. A spring, as m⁴, moves the armature m from the position seen in Fig. 2 to that seen in Fig. 40 50, when the controller is actuated into the position therein shown. From this it will be seen that the switch devices, which are movable, are moved into and held in coacting relations to the car- 55 riage or actuating means, and when the circuits are closed the retaining devices hold or retain them closed without regard to the movement of the controller on which the switch devices are mounted. It will also be 60 seen that the teeth on the actuating parts, as a and a⁴ will naturally enter into mesh with the teeth of the portions e and e⁴ of the actuating means carried by the carriage C when such portions are opposite the line of 65 movement of the switch devices, as such de- 70 vices and controller D are moved under the stress of the spring E, whether the carriage is moving in one or the other direc- 75 tion. This spring constantly tends to move the controller and switch devices into oper- 80 able position or condition, when once the controller is released from the holding ac- 85 tion of the armature m.

The controllers and the switch devices, 65 as shown, are movable into their normal po-

sitions or condition by one of the actuating parts of each pair of switch devices, when the parts are constructed, as seen in Figs. 1 to 12, inclusive, such one of these parts serving two functions, instead of a single one. The actuating parts, as a⁴, a⁵, a⁶ and a⁷, are preferably provided with but a few teeth, (two being shown,) and the same are arranged concentric with its axis of rotation, as seen in Fig. 10, and such parts sim- 70 plly rotate upon engaging with the rack teeth on the portion of the carriage which co-act therewith to close the circuit, and hence do not have any substantial tendency 75 to move the controllers against the stress of their springs. As such parts rotate they engage with their coacting movable parts and cause them to move with them, when the actuating parts are moved in a direc- 80 tion to close the circuits. Each of these ac- 85 tuating parts may be provided with a stud or projection, as s⁴, s⁵, s⁶ and s⁷, respec- 90 tively, as seen in Fig. 6, and, as indicated in dotted lines, in Fig. 10. These pins or pro- 95 jections are in position to engage with the small end of the movable parts e⁴, e⁵, e⁶ and e⁷, respectively, as indicated in Fig. 6, where actuating part a⁷ has been rotated, engaging with the small end of movable part e⁷ and in turn rotating the same and 100 closing the circuit by the contact of the pair of terminals b⁷ of switch B⁷. Each of the movable parts is provided with a pin or projection, as t, t', &c., preferably insulated from such part, to engage with one of each pair of terminals, as seen in Figs. 4 and 5. As shown in Fig. 6 the movable part e⁷ is in engagement with the portion i⁷ of retaining device I⁷ and will be held in the position seen until the part j⁷ of such 105 retaining device is acted upon by the portion J⁷, Fig. 1, carried by the carriage. Each retaining device as I, I', I², &c., is preferably forced toward its movable part, as e, e', e², &c., by a suitable spring or 110 springs, so as to move relatively thereto, as shown in Figs. 3 and 5. One of these springs, as l, is seen in Fig. 5, and each operates in the same way, as there shown, the stress of such springs tending to move the retaining 115 devices toward their respective movable parts, as indicated in this Fig. 5.

The actuating parts, as a, a', a² and a³, as before explained, serve two functions, one of which is to actuate or operate their re- 120 spective movable parts by engaging therewith, as in the case of parts a⁴, a⁵, a⁶ and a⁷ which engage with their respective mov- 125 able parts e⁴, e⁵, e⁶ and e⁷, and the other one is to move the controllers on which such parts a, a', a² and a³ are mounted from the position where the switches are in operable condition into an inoperable, or their normal condition. Instead of only a few teeth, as for instance two, as shown in the case of 130

actuating parts a^4 , a^5 , &c., a greater number are preferably employed, as for instance five, as shown, on each part, as a , a' , &c.; and also instead of these teeth being arranged concentric with the axis of rotation, as in the case of parts a^4 , a^5 , &c., they are preferably arranged eccentric thereto so as such parts rotate they have a cam action and force the studs on which they turn away from the path of movement of the carriages or actuating means to the extent of their eccentricity, the controllers in which the studs are mounted moving with such studs. In this way the controllers are moved against the stress of their springs, as E and E' , until they have reached a point where their respective armatures will engage therewith and maintain them in their normal positions, where the switch devices carried thereby are inoperable by the actuating means, as they move back and forth past them. The extent of the eccentricity of these actuating parts, as a , a' , &c., may be such as is desired by any individual constructor, so long as it serves to move the parts to the desired extent. The number of teeth employed on any of the above actuating parts may be such as is desired, such as a single one, as shown in Figs. 13 to 18, or more, and the shape and construction of the same, as well as that of the several parts, may be such as is desired, so long as the general mode of operation be substantially the same as herein set forth.

If desired a partial tooth may be used, as shown in Fig. 9 and elsewhere, on each of the actuating parts, as a , a' , &c., so as to gradually increase the eccentricity of such parts and move the controllers against the stress of the springs, as E and E' . These actuating parts a , a' , a^2 , a^3 , a^4 , a^5 , &c., are preferably held in a given position, so that they will engage with the actuating means with which they coact to close the circuits, before reaching their axis of rotation, as shown, and thus move past such axis to close the circuits. The positions actuating parts a^3 and a^4 occupy in Fig. 6 has been found in practice to be a satisfactory one for the engagement of these devices with the portions or racks c , c' , c^2 , c^3 , c^4 , &c., whether the controllers and switches mounted thereon moved from their normal or inoperative positions to the operative one before the actuating portions c , c' , c^2 , c^3 , c^4 , &c., had reached the switches, or as such portions were passing by them, in their movements relatively thereto. These actuating parts a , a' , a^2 , a^3 , a^4 , &c., are shown as being held in their given positions by two arm springs, as r , r' , r^2 , r^3 , r^4 , &c., respectively. These springs are coiled around hubs on the actuating parts and one arm of each spring extends on one side of a pin or projection, k , k' , k^2 , k^3 , k^4 , &c., on the actuating part and a pin or

projection, as u , u' , u^2 , &c., mounted on the controller, and the other arm of each spring extends along the opposite sides of the same pins or projections, as seen in Figs. 4 to 7. As here shown a single pin or projection, as u , u' , u^2 , &c., mounted on the controller 70 serves for the actuating parts of a pair of switch devices, as seen in Fig. 7. As soon as the actuating means, as c , c' , &c., engage with the actuating parts, as a , a' , a^2 , &c., they overcome the stress of these springs, as r , r' , r^2 , &c., and such parts are permitted to move until such means have operated such parts to the full extent and as such means leave, or disengage from, such parts 75 these springs immediately return the actuating parts, as a , a' , &c., to their normal or given positions, as seen in Fig. 6, whether the movable part is detained or not. These two arm springs also permit the actuating parts, as a , a' , &c., to move in the opposite direction and to then return such parts to their normal or given positions again. From this it will be seen that these actuating parts are yieldingly held in a given direction by a single spring and each is movable in two directions upon the application of force thereto sufficient to overcome the stress of such spring. 80

The retaining devices, as I , I' , I^2 , &c., are moved against the stress of their springs, as l , l' , l^2 , &c., by inclined or abutting surfaces, J , J' , J^2 , J^3 , J , &c., mounted on the carriages and arranged to abut against the ends j , j' , j^2 , j^3 , j^4 , &c., of the retaining devices I , I' , I^2 , &c., and move such devices, as retaining device I^7 is moved by abutting surface J^7 , in Fig. 1, and thereby release the movable part e^7 , as there seen, opening the terminals b^7 and the circuit connected therewith. As seen the switch device B^7 has its terminals b^7 closed, and they will remain closed until abutting surface J^6 reaches the end j^6 of retaining device I^7 in the continued downward movement of carriage C' and 95 forces it backward to the extent retaining device I^6 has been moved back by abutment J^7 . As soon as the retaining devices have been forced backwardly against the stress of their springs by the abutments, as J , J' , &c., the 100 spring action of the pairs of terminals, as b , b' , &c., will return the movable parts, as e , e' , e^2 , &c., to their normal positions, as seen in Figs. 3 and 4, and as such abutments move past and out of engagement with the retaining devices they engage with the rear circular ends of such movable parts, except as they are moved out of engagement therewith by the passage of the abutments by them or the movement of the movable parts out of engagement therewith. These rear ends of the movable parts may be given any desired shape. The form shown has been found to answer the purpose very well. 105

The controllers are released by energizing 110

the magnets, as M , M' , and withdrawing the projections, as m^2 , m^3 , on armatures, as m and m' , out of engagement with pins or projections, as g and g' , on controllers, as 5 D and D' ; and permitting such controllers to move under the stress of their springs, as E and E' . These magnets, as M and M' , and their armatures, &c., form a portion of the means by which the controllers and 10 switch devices are released, and such portions are preferably located at a given place or central station. The other portions of such means are located at the floors of a building or local stations, and such portions 15 for each floor or station preferably consist of a push button or circuit opening and closing device, with a circuit connecting with a source of energy and one of such magnets at the central station. That is, the means 20 by which each controller is released preferably consists of the magnet portion at the central station or where the controller is located, which is to be released, and another portion located at the local station or floor 25 of the building and connecting with the magnet portion to energize the same. The circuits for push button devices N and N' are as follows: from source of energy P' by wire 24 to push button N' , and thence 30 by wire 25 to magnet M' , and then, by wire 26, back to source P' ; from this same source by wire 27 to magnet M and thence by wire 28 to push button N and then, by wire 29 back to source P' . 35 As shown in Fig. 1 there are two cars, each provided with a signaling device, and a floor or local station signal for each of two floors or local stations, for each car, dia- 40 grammatically arranged. The car signals G and G' are located, one in each car, and, as before explained, each signal device in each car is to be operated as the car moves in either direction. The floor or local station signal devices H , H' , H^2 and H^3 are 45 to be operated only as the car moves in one of its two directions of movement, each car shaft being provided with separate signal devices at the floors or stations, which are operable only on the movement of that particular car. It is customary to provide two 50 sets of such separate floor or sub-station signals, one operable as the car moves upwardly and the other as such car moves downwardly, one signal device of each set 55 being arranged at each station or floor, except the upper and lower floors. As shown there is a separate switch device for each floor or sub-station signal device and for each signal to be given within each car, as 60 it moves up and down and approaches each of the floors or local stations. Also there are as many controllers as there are signal devices at each floor or station to be operated, that is one at each floor of the building 65 for the upwardly moving cars and one

for the downwardly moving cars, except the top and bottom floors or stations, that are to be served by any given system or apparatus.

The circuits by which the signal devices 70 in the cars may be operated are as follows: from source of energy P by wire 1 to wire 2 to signal device G' in car A' and thence by wire 3 to the pair of terminals b^1 of switch device B^1 on controller D' and thence by 75 wire 4 to wire 5 and back to the other side of source P , then, from source P by wires 1 and 2 to signal device G' again and thence by wire 3 to wire 6 and the pair of terminals b^5 of switch device B^5 on controller D 80 and then from such terminals by wire 7 to wire 5 and source P ; for signal device G in car A the circuits are from source P by wire 1 to wire 8, thence to device G and thence by wire 9 to the pair of terminals b^3 85 of switch device B^3 on controller D' and then by wire 10 to wire 5 and back to the other side of source P ; then from source P by wires 1 and 8 to device G again, thence by wire 9 to wire 11 to the pair of terminals b^1 90 of switch device B' on controller D and thence by wire 12 to wire 13 to the other side of source P .

The circuits for the floor or station signal devices H , H' , H^2 and H^3 are as follows: 95 from source P by wire 1 to device H^3 , thence by wire 14 to the pair of terminals b^6 of switch device B^6 on controller D' and thence by wire 16 to wire 5 and back to source P ; from source P by wire 1 to device H^2 , thence 100 by wire 17 to the pair of terminals b^4 of switch B^4 and then by wire 18 to wire 5 and the other side of source P , from source P by wire 19 to device H' , thence by wire 22 to the pair of terminals b^2 of switch B^2 and 105 then by wire 23 to wire 13 and the other side of source P ; from this source again by wire 19 to device H and thence by wire 20 to the pair of terminals b of switch device B and by wire 21 to wire 13 and thence to source P . 110 As thus shown a person on the floor or at the substation where push button device N' is located desiring to signal the first car going in a downwardly direction he would actuate the push button device N' , which 115 would energize the electromagnet M' , release controller D' and permit spring E' to move such controller and the switch devices carried thereby into operable position or condition so that each device thereon could 120 be operated by its particular car. Then the first one of the two cars, A and A' , which reached its particular switch device on controller D' would have its carriage or actuating means in position to engage with the 125 actuating parts of that particular pair of switch devices and actuate them as such means first engaged therewith and closing the circuits connected thereto, the actuating part, as a' , a^3 , a^5 and a^7 , of each pair of de- 130

5 vices continuing to rotate on its stud and moving the controller against the stress of its spring into position for it to be held by the projection on the armature of its elec-
 10 tromagnet, where it would be held or maintained until the push button device N' was again operated. After the actuating and movable parts of such pair of switch devices had closed the circuits the retaining devices
 15 connected therewith would, under the stress of their respective spring or springs, move into position to engage with such movable parts, after the actuating means cease to control their movements, and hold the cir-
 20 cuits closed for the desired extent of movement of the actuating means, when the abut-
 25 ment or abutments or abutting surfaces, as J , J' , J^2 , and J^3 , which are to abut against the forward end or ends of such retaining
 30 devices will force such devices out of eng-
 35 gagement with such movable parts and the circuits will be broken by the opening of the pair or pairs of terminals with which they connect when the signal devices will cease to operate until the switch devices are moved from their inoperable condition to the operable, and the actuating means has again closed such circuit or circuits. From this it will be seen that the car and carriage
 40 which first reaches a position to actuate a pair of switch devices, after they have been brought into operable condition or position, and the actuating means operate the same restores or returns such switch devices, with
 45 all other pairs mounted to move with them, to their inoperable condition, or normal po-
 50 sitions. It will also be seen that the circuits remain closed, after the switch devices and controller have been restored or returned to their normal positions, or the positions where the switch devices are inoperable by the actuating means, and until the coacting abutment or abutments, as J , J' , &c., actuate the retaining devices, as described. That is, the opening of the circuits are not dependent necessarily upon the movements of the parts which were actuated to close them. Because of this peculiarity of this construction the portions, as c , c' , c^2 , &c., of the actuating
 55 means may be of any desired proportions, so that the signal devices for any given floor or substation may be made to operate at any given point in the movement of the car relatively to any given floor. For instance, if it is desired that the floor or station signal shall begin to operate, say when the car has reached a point three floors or stations of the one where the push button device is located the parts or portions, as c^4 c^5 , &c., will
 60 be long enough to engage with the switch devices corresponding to the floor where the push button is located to do this, and then the signal device for that floor will begin to operate when three floors or stations away

and continue to operate until the car has 65 reached a point where it is desired to have such signal cease operation, as, for instance, when the car has just passed by the floor or station where the push button is located, or any other desired point. 70

Sometimes it is desirable that a car shall not be stopped by the operator too quickly, as, for instance, within a distance of that between two ordinary floors of a building, or some other distance and that the signals in 75 the car and at the floor shall not be given when a car has reached a point within such distance. If it is desired to do this these portions, as c , c' , c^2 , c^3 , c^4 , &c., may be cut short, as shown in Fig. 1, so that there is a 80 distance corresponding to two ordinary floors between such portions at one end of the carriage and the corresponding portions at the other end, one half of such distance being as the car approaches the floor in one 85 direction and the other half as it approaches that floor in the other direction. Then, when a car has approached within one floor of the point where a push button device is 90 located and such device were to be operated, no signals would be given by the continued movement of that car and would be given by the next approaching car moving in the same direction. The distance between the two portions of the actuating means may be 95 made such as is desired in each individual system or apparatus.

Sometimes it is desired that the signal de-
 100 vice in the car shall not begin to operate until some little time after the device at the floor or station has begun to operate. When this is desired the portions, as c , c' , c^2 , &c., may be made as shown in Figs. 1, 11 and 12, or otherwise, as desired. Also the abutments, as J , J' , &c., may be arranged so 105 as to cause the signals to cease operating at different times, also as shown in Fig. 1, as each switch device is operably independent of each of the others, and each retaining device is also operably independent of the 110 others, hence each switch device may begin and cease to operate at any desired point in the movement of the car and carriage relatively thereto.

The use of teeth or a roughened surface 115 for the actuating means and actuating parts to engage with permits the actuating parts to be carried by the controllers and to be quickly and surely operated when brought into operable position, as the portions of the actuating means, as c , c' , c^2 , c^3 , c^4 , &c., are passing by such parts. These teeth or surfaces also permit the switch devices and controllers to move substantially their full extent into their operable condition as such portions are in the path of movement of such switch devices. This is the case whether the actuating means be at the moment mov- 120 125

ing in one direction or the other, or is momentarily standing still in such path of movement.

The springs which are shown as moving the controllers and switch devices into operable condition or positions act continuously, exerting their force to move such controllers in one direction and opposing their movement in the other direction. Thus when these controllers have reached the limit of their movement under the stress of their springs such springs hold them in such positions until an overpowering force moves them therefrom. Such springs also hold the actuating parts of the switch devices in engagement with the actuating means and thus insure the proper actuation thereof. They do this at all times whether the car backs up or down, as when it has run past a floor or in the regular operation of the car.

Instead of employing the form of switch devices seen in preceding figures other forms or constructions may be employed, which embody in substance the combinations of members or devices particularly pointed out in some of the claims hereunto annexed. As for instance such as are shown in Figs. 13 to 18, inclusive, where special retaining means to hold the circuits closed are not employed. The actuating means mounted to move relatively to the switch devices in a measure do the work done by the special retaining means shown in preceding figures of the drawings. In Figs. 13 to 18 only one switch device is shown, but pairs of such devices may be employed, if desired, by simply duplicating the pair of terminals there seen, the lever which coacts therewith, the two arm spring and the portion of the actuating means, which operates said lever, as the same are here shown. Of course in that case the stud on which such lever is mounted and the pin or projection on the controller with which the two arm spring coacts would have to be increased in length to receive and hold the lever and spring. Each controller, as D^2 , may support as many individual switch devices, as desired, whether it be one or more. Each switch device, as B^8 , may consist of a pair of terminals as b^8 , an actuating lever, as a^8 , a two arm spring, as r^8 , and a stud, as d^8 , mounted in controller, as D^2 . The actuating lever a^8 has only one tooth, instead of several teeth, as in preceding figures, and is, as shown, arranged to engage with the teeth on the portion c^8 of the actuating means and move equally in two directions, accordingly as the actuating means, as C^2 , moves. This lever, as a^8 , in moving in one direction closes the circuit through terminals, as b^8 , as seen in Fig. 16, and in moving in the other direction moves away from such terminals, as seen in Fig. 17, and the circuit remains open.

The controllers carrying switch devices, as

B^8 , may be provided with springs arranged as springs E and E' are arranged in Fig. 1, and such controllers may be held or maintained in positions where the switch devices, carried thereby are inoperable upon the passage of the actuating means mounted to move relatively thereto in the same manner and by the same kind of means as are employed in connection with controllers D and D' of that figure, or other means, and they may be released by the same or any other desired kind of means, and hence the switch devices are movable from their inoperable to their operable condition and back again. The means shown by which each of these controllers are moved from the position where the switches are operable to the position where the switches are inoperable are of substantially the same general character as those seen in preceding figures, but they are so arranged therein, or combined together, that the actuating means maintain the circuits closed during the desired extent of movement of the car without the aid of other and separate devices and then the controller and its switches are restored or returned to their normal positions with the switches in their inoperable condition. The actuating means for one car, when moving in one direction as C^2 , are shown more or less in Figs. 13, 14, 16 and 17, and such means may be mounted to move relatively to the switch devices in like manner that the carriages or actuating means C and C' are mounted to move, in Fig. 1. The teeth in the portion c^8 of actuating means C^2 , with which the levers, as a^8 , engage, are shown as made of a greater depth than the teeth shown in preceding figures. This causes the levers to be moved a greater distance before passing out of mesh with the rack teeth and sliding over the remaining teeth while holding the circuits closed. When any actuating lever is moved into engagement with its actuating means, as such means are passing the lever, it will be actuated the same as if such lever was brought into the operable position before such means had reached it, but it will not be held in the actuated or operated position for so great an extent of movement of such means, as when such lever is in such position before the means has reached it. The operation is substantially the same in one case as in the other. In this respect the operation of these actuating levers is somewhat like that of the actuating parts in preceding figures, so far as concerns the action of the actuating means thereon before reaching and in passing by such parts.

A restoring part, as a^9 , substantially of the construction seen in Fig. 9, but of greater eccentricity, is mounted on the same stud as actuating lever a^8 is mounted, and it is provided with a two arm spring, as r^9 , as shown in preceding figures and more particularly

in Fig. 18. On the carriage or actuating means C^2 there is mounted a short section of a rack, as c^{10} , in position to engage with restoring part, as a^9 , and as such part rotates 5 on its stud to force it and the controller into position to be held by the means provided for this purpose, that is, into the position where the switches are in their inoperable condition, and the teeth on the parts c^8 and c^{10} will not engage with the parts a^8 and a^9 . As shown in these Figs. 13 to 18 a stud or projection, as g' , on the controller, as D^2 , engages with a projection, as m^8 , on armature, as m^6 , which is mounted to coact with 10 electromagnet M^2 . A spring, as E^2 , engages with the end of controller, as D^2 , and with a portion of the bar Y^2 , the stress of which continuously tends to move the controller D^2 toward the carriage, as C^2 , and to bring the 15 parts, as a^8 and a^9 into position to be engaged with parts c^8 and c^{10} , respectively, the controller and the parts carried thereby being held against this tendency by the armature, as m^6 , and spring m^9 , in like manner that 20 each of the controllers is held in preceding figures. The controller, as D^2 , may be released from the restraint of armature, as m^6 , by energizing electromagnet M^2 , as in preceding figures, or otherwise. 25 In Figs. 13 and 15 the pair of terminals, as b^8 , and the controller, as D^2 , are shown in the positions they occupy when moved into position to have actuating means c^8 and c^{10} engage with lever, as a^8 , and controller restoring part or device, as a^9 , to first operate 30 the signal device and restore the controller and parts supported thereby to the control or restraint of the armature, as m^6 . In Fig. 35 16 the portion of the actuating means, as c^8 , has moved in the direction of the arrow sufficiently to engage with the lever, as a^8 , actuate the same and close the terminals, as b^8 , and as such portion continues to move the end of the lever in engagement there- 40 with moves with it and the terminals are held in contact until the last tooth on the portion, as c^8 , has passed beyond the lever, as a^8 , when the two arm spring, as r^8 , returns such lever to its normal position, as 45 seen in Figs. 13 and 15. When this has occurred the restoring part or device, as a^9 , engages with the part, as c^{10} , which is in a different plane from that of c^8 , as seen in Fig. 14, and as such part continues to move 50 the eccentric or cam part, as a^9 , rotates on its stud or support, as d^8 , and the controller is forced away from the path of movement of the carriage, as C^2 , until it is engaged with the armature, as m^6 , and the lever, as 55 a^8 , is out of position for the portion, as c^8 , of the actuating means to engage therewith, and, hence, such lever and the switch device are inoperable, and are in what may be aptly termed their inoperative positions or 60 condition. It is desirable that the controller 65

or controllers, as D^2 , shall always move into the operative position, when once released from the restraining or holding action of the armature or armatures, as m^6 , to substantially the full extent of their movement, 70 whether the actuating means be in position to engage therewith or not, and also whether such means be moving in one direction or the other. This is accomplished in the construction seen in these Figs. 13 to 18, as it 75 is also, in the case in preceding figures. The tooth on this lever, as a^8 , or the teeth on the parts, as shown in Figs. 9 and 10 engage with the rack teeth on the actuating means as soon as such means are in position 80 for this to be done, and if such means move in one direction the switch terminals are closed, but if such means move in the other or opposite direction, then the switch terminals are not disturbed, because the coacting parts are moved in the wrong direction in such case and the switches will not be operated. This is illustrated in Fig. 17 of the drawings. As there shown the portion, as c^8 , of the actuating means is moving in 85 the opposite direction to that in which the same means are shown as moving in Fig. 16, and the result is that the lever, as a^8 , is moved away from the terminals, as b^8 , of switch B^8 , and of course such terminals are 90 not disturbed in the least and consequently remain open. The action of the portion, as c^{10} , of the actuating means upon the cam or eccentric part, as a^9 , when such means move in the direction of the arrow, as indicated in 95 Fig. 17, is to move the cam face or portion of such part away from the portion, as c^{10} , and as a consequence the controller, as D^2 , remains undisturbed and is not forced 100 against the stress of its spring, as E^2 , to 105 any substantial extent, and such means may pass by such switch device leaving it unoperated and ready to be operated, when such means move in the proper direction to do this. 110

The operation of the parts seen in Figs. 9 and 10 is substantially the same as of the parts seen in Figs. 13 to 18, in the above respect, as well as in some others. Thus it will be seen that these movable parts, as a^3 and a^7 of Figs. 6 and 7 and as a^8 and a^9 of Figs. 13 to 18, are actuatable by the springs, as E , E' and E^2 , into engaging position or relation with their coacting parts, as c^3 and c^7 and c^8 and c^{10} , which are mounted to move 115 relatively to such movable parts in two directions, and that such parts are held in such engaging position or positions by springs, as E , E' and E^2 , and that each part may move in either of two directions, accordingly as such coacting portions move in one or the other of such directions; also that such coacting portions are adapted to move such cam or eccentric parts relatively to the controller or controllers and restore the 120 125 130

switch device or devices to their normal positions or conditions, that is, where the switches are in their inoperative condition. In these Figs. 13 to 18 the two arm springs operate the same as in preceding figures, notwithstanding that the stationary or fixed pin or projection attached to the controller occupies a different position relatively to the pins or projections on the movable and actuable parts by the movement of which the switches are operated and the circuits closed from the positions shown in such other figures. In Fig. 18 the fixed pin or projection u^8 is attached to the controller, and the pins or projections u^5 and u^6 are attached to the movable parts a^8 and a^9 , respectively. As thus arranged the fixed or controller pin or projection is the farthest from the stud on which the movable parts turn, in these Figs. 13 to 18, while in preceding figures this fixed or controller pin is the one nearest the stud. Switch devices, as B^8 , may be connected with the circuits, signal devices, source or sources of energy and push button devices, in substantially the same manner diagrammatically illustrated in Fig. 1, if desired, or in other desired manner or manners.

Instead of employing switch devices of the general character seen in preceding figures switch devices of the general character of those shown in Figs. 19, 20, 21 and 22 may be employed with like results in many of the combinations hereinafter pointed out without changing or materially affecting the mode of operation of each of such combinations. Switch devices of this general character are shown and described in an application Serial No. 234,357, filed November 26, 1904. The switch devices, as B^9 and B^{10} , are here shown as mounted on bars or controllers, as D^3 and D^4 which in turn are mounted in bars, as Y^4 , Y^6 having springs, as E^4 , and E^6 to move the controllers into position where the terminal or terminals of the switch devices may be closed, all substantially as in the case of the controllers seen in preceding figures. That is, the means for moving the controllers to bring the switch devices into operable condition, to hold them there, to hold or retain them in their inoperable condition and to release them may be of the general character or constructions, seen in preceding figures, or be varied therefrom so long as the mode of operation of each of such combinations be not materially changed. In the construction here shown the movable or actuable parts with which some portion of the actuating means co-act in order to close the terminals and operate the signal devices are not mounted on the controllers or movable bars, as D^3 or D^4 , but are separately mounted and are normally in position to be actuated by the means mounted

to move relatively thereto and adapted to do this work. In Figs. 19, 20 and 21 such actuable part, as a^{12} , is mounted on a fixed support in the form of a stud or pin v mounted in a bar or standard V affixed to the frame of the machine in any convenient way to hold such actuable part in position. In Fig. 21 this actuable part is shown in its normal position, always ready to be operated by the movement of the carriage, as C^4 , and the portion, as c^{12} , past it in either direction of its movement relatively thereto. The controller D^3 and switch device B^9 are also here shown in position for the circuit or circuits to be closed upon the actuation of the lever, as a^{12} , by the portion of the actuating means, as c^{12} , moving upwardly, or in the direction indicated by the arrow in Fig. 19 into the position there shown where the terminals, as b^9 are closed and will remain closed until the abutting portion of such means, as c^{12} , has passed entirely beyond and out of engagement with such lever and it is free to assume the position seen in Fig. 21. This lever, as a^{12} , is also preferably provided with a two arm spring as r^{12} , best seen in Fig. 20, acting substantially in the manner that the other two arm springs, heretofore described, act. This spring, as r^{12} is mounted on the hub of lever, as a^{12} , and one arm passes under and at one side of two pins or projections, as u^{12} and u^{13} , and the other arm of such spring passes under and at the opposite side of these same two pins or projections. One of these two pins or projections, as u^{12} , is secured to the lever, as a^{12} , and the other one, as u^{13} , is affixed to the standard or bar V . The controllers, as D^3 and D^4 are preferably returned or restored to their normal positions, that is, the positions where the switch devices are in an inoperable condition by a portion on the actuating means and a coacting roller or abutting surface on the controllers the two things coacting together to accomplish this work.

As shown in Figs. 19 and 20 an abutment or roller, as o is suitably mounted on controller D^3 with which a surface preferably inclined, on a piece or portion, as n , coacts, which is mounted on the actuating means so as to move therewith and through the action of one on the other the controller is forced endwise away from the path of movement of such actuating means into its normal position where it will be held until again released, as before explained. There are two of these abutments, as n and n' , shown, one, as n , to act on the "up" controllers, as the carriage moves in one direction and the other, as n' , to act on the "down" controllers, as the carriage moves in the other direction, each having the same mode of operation. The carriage and actuating means are preferably to be substantially divided

midway of their length, and each division is a substantial duplicate of the other and are made to coact with their respective parts or switch devices in substantially the same way to produce the same result. These parts, as n and n' , are preferably pivotally attached to the actuating means and yieldingly held in their normal position by springs as shown or otherwise, as desired. 5
 10 When thus attached these parts, as n and n' , yield, as the actuating means move in one direction and permit such parts to pass by their respective controllers without actuating them, but are held against yielding 15 when such parts move with the actuating means in the other direction and when so held they operate the switch devices and restore the controllers to their normal position or positions as more clearly explained 20 in said application. If desired only one terminal of each switch device may be carried upon the controllers and yet substantially the same mode of operation be had, as if both terminals were thus carried, as indicated in Fig. 22. In this figure, as in preceding figures a portion of the controller is broken away to better show the parts directly behind it.

As shown in Fig. 22 one of the pair of terminals, as b^{10} , is mounted on a block, α , preferably of insulating material, which block is shown as secured to the bar or standard V' , to which lever, as a^{12} , is pivotally affixed, and hence is always in position to be actuated by such lever, when moved in one direction by the action of the actuating means, (not shown, but of substantially the same construction as means c^{12} , seen in Figs. 19 to 21,) which are mounted on a carriage to move relatively thereto and actuate such lever, as lever a^{12} is actuated in these Figs. 19 to 21, and with like results. As shown in this Fig. 22 the controller, as D^4 , is in the position that the part, as a^{12} , when actuated, would not move the terminal mounted on the block α into contact with its companion terminal carried by the controller, as D^4 , but when the controller is released and is free to move under the stress of its spring, as E^5 , it will be moved toward the right into position, so that upon actuating such lever, as a^{12} , the two terminals, as b^{10} will be brought into contact one with the other and the circuit closed, the same as in preceding figures of the drawings. Otherwise the operation of this construction is the same as that shown in Figs. 19 to 21, inclusive, and will be fully understood without further explanation.

In each of the constructions herein shown and described the circuits are normally in an inoperable condition by reason of the switch devices being normally in positions where their terminals cannot be brought into contact by the means provided for

that purpose. These switch devices and the circuits controlled by them are to be brought into operable condition as desired by any suitable means desired to be operable from a floor or station from which a signal is to be sent and given in the desired position or positions, and for the desired length of time or extent of movement of a car or similar moving object. The portions of such means which are operable from the floors or stations are of such a construction and arrangement that the switch devices are released and continuously acting means move such devices from a position or positions where they cannot be operated into a position or positions where they are operable, and are held there by such continuously operating means until the signals are given and the controllers are returned or restored to the position or positions where the switch devices are again inoperable. 70 75 80 85

What is herein shown and described will naturally suggest to the minds of those skilled in the art to which this invention pertains other constructions of parts and embodiments of the present invention by which equivalent means combined in substantially the same manner and having the same mode of operation will accomplish equivalent work, and, hence, I wish to be understood as including within the present invention all such constructions or embodiments and do not wish to be limited to the specific constructions and embodiments herein shown. 90 95 100

What I claim as new is:—

1. In a signal apparatus the combination, of a circuit, a switch device connected therewith having two pivotally mounted parts, one of which is movable in one direction by the movement of the other, holding means adapted to engage with the moved part and hold it in the displaced position, and means adapted to move relatively to the switch device and engage with a portion of the holding means and release the moved part. 105 110 115

2. In a signal apparatus the combination, of a circuit, a switch device connected therewith having two levers pivotally mounted on the same axial line one adapted to engage with one terminal of the circuit and the other to engage with the first lever and also with actuating means, and actuating means adapted to move relatively to such levers to actuate the same and close the switch. 115 120

3. In a signal apparatus the combination, of a circuit, a switch device connected therewith having a movable part adapted to engage with one terminal of the circuit, means adapted to move relatively to the switch device in two directions and to actuate such part to close the circuit in only one direction of movement, a retaining device adapted to engage with such movable part after the circuit is closed, and actuating means also 125 130

- movable relatively to the retaining device in two directions of movement and adapted to engage with a portion of the retaining device to actuate it into position to release 5 the movable part for opening the switch.
4. In an elevator signal apparatus, in combination, a signal circuit, a switch in said circuit, a traveler moving correspondingly with the car and arranged to move 10 said switch to close the same, means other than said traveler for holding said switch closed, and means for reopening said switch.
5. In an elevator signal apparatus, in combination, a signal circuit, a switch in 15 said circuit which may close said circuit, a traveler moving correspondingly with the car and arranged to move said switch to close the same, and retaining means for holding said switch closed and arranged to 20 be released by said traveler.
6. In an elevator signal apparatus, in combination, a signal circuit, a switch in said circuit, a lock for said switch when moved into its closed position, a traveler 25 moving correspondingly with the car and arranged to close said switch at one point of its travel, said traveler having means for unlocking said switch at another point of its travel.
30. 7. In an elevator signal apparatus in combination, two cars, a traveler moving correspondingly with each car, a signal corresponding to each car, an electric circuit for each signal, each circuit having a normally 35 open switch device therein past by the travelers, each switch device having a part adapted to be engaged and moved by its corresponding traveler to close the circuit, and a lock for holding the switch closed, said 40 part of each switch device being normally in position such that neither traveler can engage the same to close its circuit, a passenger's-button at a floor, means controlled by said passenger's-button and causing said 45 switch parts of each switch to move into position such that each traveler will engage the same to close its switch, and restoring mechanism operated by each car and operating to restore said passenger's-button-controlled parts to normal position.
50. 8. In an elevator signal apparatus in combination, a signal circuit, a switch in said circuit, a traveler moving correspondingly with the car and arranged to move said switch to close the same, means other than 55 said traveler for holding said switch closed, means for reopening said switch, one of the parts of said switch being normally in a position such that the traveler cannot close 60 the switch, a passenger's-button, and means operated thereby and causing said switch part to move to a position such that the traveler may close the switch.
65. 9. In an elevator signal apparatus in combination, a signal circuit, a switch in said 70 circuit, a traveler moving correspondingly with the car and arranged to move said switch to close the same, means other than said traveler for holding said switch closed, and means for reopening said switch, said traveler being capable of closing said switch in only one direction of the car's movement.
10. In an elevator signal apparatus, in combination, a plurality of cars, a plurality of travelers corresponding to said cars, signal circuits leading to said cars, floor signal circuits leading to the floors, independently movable circuit closers for closing said circuits, and means for moving said circuit closers into the paths of said travelers to be 75 actuated by said travelers.
11. In an elevator signal apparatus, in combination, a plurality of cars, a plurality of travelers moving correspondingly therewith, signal circuits, a controller, circuit 80 closers movably mounted on said controller and adapted to close said circuits when actuated by said travelers, means for moving said controller to bring said circuit closers into the paths of said travelers, and means 85 for effecting the return of said controller by the actuation of said circuit closers.
12. In an elevator signal apparatus in combination, a car, a signal circuit, a circuit-closer for said signal circuit comprising a dog arranged to close the circuit when moved, a driver moving independently of said dog and adapted to actuate the same to close the circuit, and means moving correspondingly with the car adapted to engage and actuate said driver, means for yielding 90 holding said driver in its normal position, said driver and said dog being constructed so that said driver will actuate said dog in one direction of movement only.
13. In an elevator signaling apparatus in combination, a plurality of cars, a plurality of signal circuits, a plurality of circuit-closers for said signal circuits, a controller carrying all of said circuit-closers corresponding to one floor, said circuit-closers comprising dogs for closing the said circuits and drivers movable independently of said dogs for actuating said dogs, travelers moving correspondingly with said cars and 100 adapted to actuate said drivers, said dogs being pivoted on said controllers and comprising cams engaging said travelers and adapted to move said controller to return the same.
14. In an elevator signaling apparatus in combination, a plurality of cars, a plurality of signal circuits, a plurality of circuit-closers for said signal circuits, a controller carrying all of said circuit-closers corresponding to one floor, said circuit-closers comprising dogs for closing the said circuits and drivers movable independently of said dogs for actuating said dogs, travelers moving correspondingly with said cars and 105

inoperative position to an operative position, detent mechanism for each controller holding it in its normal inoperative position, electro-magnetic mechanism for releasing said detent mechanism, a passenger's switch located at each of said floors and each adapted to cause its corresponding electro-magnetic mechanism to be energized, restoring mechanism comprising a movable device for each car moved correspondingly with but much slower than said car, each of said devices being adapted to mechanically move said signal controllers in succession back to normal position and allow said detent mechanisms to thereafter hold the same, said signal controllers, detents and movable devices being grouped together.

20. In an elevator signaling apparatus in combination, a pair of shafts and cars, normally-inactive electrically-operated signals for the operators of said cars, a passenger's button at a floor, a signal controller corresponding to said floor adapted to at least in part control the signals of both said cars and

in a given location with relation to the movement of said cars but slightly movable, detent mechanism controlled by said push-button and adapted to normally hold said controller, restoring mechanism comprising a car-operated part for each car moved correspondingly with but much slower than its car, and intermediate mechanism between said controller and both said car-operated parts, said intermediate mechanism being constructed and arranged to have an automatic tendency to move in one direction and adapted to be mechanically moved in the opposite direction by said car-operated parts and thereby move said controller back to its detent-engaged position, said intermediate mechanism then automatically returning to its own normal position after said car-operated parts have passed away from the same. 25 30 35 40

HENRY F. NEWBURY.

Copies of this patent may be obtained for five cents each, by addressing the "Commissioner of Patents, Washington, D. C."

It is hereby certified that in Letters Patent No. 1,132,606, granted March 23, 1915, upon the application of Henry F. Newbury, of New York, N. Y., for an improvement in "Signal Apparatus" an error appears in the printed specification requiring correction as follows: Page 13, line 12, before the word "said," second occurrence, insert the word *each*; and that the said Letters Patent should be read with this correction therein that the same may conform to the record of the case in the Patent Office.

Signed and sealed this 13th day of April, A. D., 1915.

[SEAL.]

J. T. NEWTON,

Acting Commissioner of Patents.
